SOUND RECORDING SYSTEM

Arthur C. Blaney, Los Angeles, Calif., assignor to
Radio Corporation of America, a corporation of
Delaware

Application August 5, 1939, Serial No. 288,613

14 Claims. (Cl. 179—100.3)

This invention relates to sound recording systems and particularly to the recording of sound on motion picture film.

It is the general practice in motion picture studios to record sound in related and unrelated sequences which are spliced together at the end of the day and processed. The picture sequences are also photographed and treated in the same manner. The sound and picture negatives are then printed individually but reproduced in synchronism for inspection the next day. Certain sequences or sections of sequences are marked for deletion at this inspection, while subsequent editing eliminates and interchanges other picture and sound sequences to form the story continuity. For this purpose one or more sound prints from the original negative may be made and used. When the final cutting or editing has been completed, the original negative is then cut to complete with the final edited print, from which original negative a new print is made for rerecording purposes. The rerecording step produces the final negative from which the combination picture and sound print is made for release to the theatres. An individual sound print may, sometimes, however, be used in theatres for preview showings. It is realized from the above that several printings and several processings are required before the final print is produced, each step providing the opportunity for, and generally, introducing some distortion and noise.

Sound motion picture studios are, however, aware of a type of sound recording system known as the reverse negative or direct positive system, such as disclosed and claimed in copending application Serial No. 168,173, filed October 9, 1937. This system produces a positive record by the original recording and one which is suitable for reproduction, thus eliminating the necessity of a printing step and a print. Although this system has many advantages, such as being a much quieter sound track from the ground noise standpoint, it is general practice to make a negative therefrom in order to obtain additional prints for editing and inspection purposes. However, the direct positive system does provide an immediate record after one processing step which may be used for the first daily inspection and is particularly good for rerecording purposes.

The present invention is directed to a recording system which provides on the same film both a direct positive record which may be immediately reproduced and also a negative record of the same sounds on the same film strip, identical portions of the sounds being opposite one an-

other on the film. That is, each sound track area occupies approximately 100 mils transversely of the film adjacent the sprocket holes so that each track is completely separated, one track being a very quiet positive and the other a negative, after processing.

This double track recording system is now used as follows: Although the direct positive track may be reproduced for inspection and sometimes is, prints are made from the negative track only, these prints being used for inspection and editing. The double track film is then cut according to an edited print, which automatically cuts both the negative and direct positive tracks. Now instead of having to make another print from the negative for rerecording purposes, the cut direct positive may be employed for rerecording, this track being not only superior by being more quiet than a print made from the negative, but it saves the time and cost of making a rerecording print. It also sometimes occurs that a preview is given wherein the picture is projected from one film and the sound is reproduced from a separate sound film. The quiet direct positive may be used for this purpose.

Also, certain types of sound tracks, such as push-pull tracks requiring special reproducing apparatus not in general use in theatres, have been found advantageous for the original recording in the studios where such special reproducers are available. Thus, this type of sound track is used for the direct positive for use in the studio, while the adjoining negative track may be of the standard form for universal use, although it may also be of the push-pull type for studio use.

The principal object of the invention, therefore, is to facilitate sound recording in the production of motion pictures.

Another object of the invention is to simultaneously record one type of sound track adjacent and opposite a second type of sound track on the same film.

A further object of the invention is to simultaneously record a positive sound track and a negative sound track of the same sounds on the same film.

A further object of the invention is to record a sound track immediately reproducible after processing along one portion of a film and simultaneously record a second sound track from which reproducible prints may be made along another portion of the film.

Although the novel features which are believed to be characteristic of this invention are pointed out with particularity in the claims ap-

pended herewith, the manner of its organization and the mode of its operation will be better understood by referring to the following description read in conjunction with the accompanying drawing forming a part thereof in which—

Figure 1 is a diagrammatic view of a recording system embodying the invention; and

Figure 2 is a film representing the type of sound tracks produced with the system of Fig. 1.

Referring now to Fig. 1, a pair of light sources represented by filaments 5 and 6 produce light which is collected by respective condenser lenses 8 and 9 for projection through respective masks 10 and 11. The light through the mask 10 passes a pair of noise reduction shutters 13 under control of a solenoid 14 connected in the standard manner to a noise reduction unit as disclosed and claimed in U. S. Patents 2,102,776; 2,102,777; and 2,102,778. The light passing the mask 10 is projected on a galvanometer mirror 16 having an actuating coil 17 connected to a signal source as shown in the above-mentioned patents.

The light passing the mask 10 and shutters 13 and striking the mirror 16 is projected on a slit mask 20 having a slit 21 therein, the light beam at times of no signal being shown by shaded area 22 on the mask 20. The light passing the slit 21 is projected on sound track area 26 of a film 24 by projection lenses 25.

The light passing through mask 11 is also projected upon the galvanometer mirror 16 and then reflected to a slit mask 27 having a slit 28 therein, the light beam at times of no signal being represented by the shaded areas 30. The light passing the slit 28 is projected on sound track area 32 of the film 24 by projection lenses 31.

The type of aperture in mask 10, noise reduction shutters 13, and the vibration of mirror 16 produce a standard duplex bilateral variable area sound track, while the mask 11 with its solid portions 34 and 35 and the vibration of mirror 16 produce a push-pull class-B sound track of the direct positive type, as disclosed and claimed in the above-mentioned copending application. Referring to Fig. 2, the standard duplex track is shown along the left-hand side of the film and comprises opaque zero signal lines 37, a single frequency modulation 38 for purposes of illustration, and bias shutter traces 39, the darkened areas being the opaque portions of the film and the other portions being transparent. This is a negative track and, in printing, the opaque and transparent areas are reversed to produce the normal positive antiground noise sound record. On the right-hand side of the film 24, the modulated areas 41 and zero lines 42 are transparent and the remaining areas 43 are opaque, thus representing a positive sound track record of the class-B type.

The sound track 32 is immediately reproducible, while the negative 26 must be printed to produce the usual type of commercial print. The track 32 is also quieter than a printed track made from the negative 26 and thus is superior for reproduction and rerecording purposes. It requires, of course, a reproducer with the push-pull type of reproducing elements and circuit, but this equipment is available in motion picture studios. The prints made from the track 26, on the other hand, are reproducible in all standard equipment and may be used universally. This method of recording, therefore, provides a higher quality final print since it eliminates a printing step and a processing step and utilizes a pre-

ferred form of original recording for rerecording. It correspondingly reduces time and expense.

It is to be understood that the forms of the simultaneously made tracks may be varied or changed without departing from the spirit of the invention. For instance, both tracks may be of the push-pull type since both are reproduced for inspection or rerecording purposes on studio equipment, the rerecorded negative, however, being of the present standard type for release. 10

I claim as my invention:

1. The method of sound recording comprising simultaneously recording a negative record and a direct positive record on the same film of the same sound waves. 15

2. The method sound recording in accordance with claim 1 in which said negative record has a type of sound track different from that of said direct positive.

3. The method of sound recording comprising 20 simultaneously making a direct positive record and a negative record of sound waves, printing editing prints from said negative record, and rerecording from said direct positive record to produce a final release print negative. 25

4. The method of sound recording comprising simultaneously making a negative record and a direct positive record of sound waves, printing editing prints from said negative, rerecording said direct positive record to a second negative 30 record, and printing release prints from said second negative record.

5. A sound film comprising a negative sound record and a direct positive sound record of the same sound waves on the same film. 35

6. A sound film in accordance with claim 5 in which said negative record has a track of a type different from that of said direct positive.

7. A sound film in accordance with claim 5 in which the same sounds in each record are oppositely disposed transversely of said film. 40

8. A sound film in accordance with claim 5 in which one of said records is a standard type of sound track and the other of said records is a push-pull type of track. 45

9. The method of sound recording comprising simultaneously making a direct positive record and a negative record of sound waves, making a print from said negative record, editing said print, cutting said negative record and said direct positive record to conform to said edited print, and rerecording said direct positive record to a second negative record. 50

10. The method of sound recording in accordance with claim 9 in which said second negative record is printed to make release prints. 55

11. A sound recording system comprising means for recording sound waves as a negative sound record upon a film, and means for simultaneously recording said sound waves as a direct 60 positive sound record on said same film oppositely disposed from said first record transversely of said film.

12. A sound recording system comprising means for recording sound waves as a negative 65 sound record, and means for simultaneously recording said sound waves as a direct positive sound record, both of said means including a common element for recording on the same film, said element being a light beam modulator upon which said sound waves are impressed. 70

13. A sound recording system comprising a plurality of light sources, a plurality of respective optical units for projecting light from said light sources to a film, a plurality of respective masks 75

for determining the type of sound track to be recorded by each of said units, and a light beam modulator common to said light sources, optical units and masks for simultaneously recording 5 sound waves impressed on said modulator, one respective light source, optical unit and mask producing a negative sound record, and another respective light source, optical unit and mask producing a direct positive sound record.

10 14. A sound recording system for recording the same sound waves in a plurality of sound record

tracks upon the same film, comprising a plurality of individual recording units for producing said tracks on said film, one of said units producing a negative sound record and another of said units producing a direct positive sound record, and a light modulator common to all of said recording units and upon which said sound waves are impressed as electrical currents substantially corresponding in frequency and amplitude to said sound waves. 5
